PUNCH ALIGNING IMPLEMENT

Joy E. Penrod, Muncie, Ind.

Application July 23, 1946, Serial No. 685,681

3 Claims. (Cl. 164—124)

1

This invention has for its object the providing of an implement for facilitating the aligning to true position of any one of the several punches which are embodied with and which form a part of the conventional die of a machine of the power press type.

By the term "die," as used herein, is meant the conventional assembly which consists of a base plate adapted to rest on the bolster of the machine, and from said base plate rise leader pins whose upper portions are slidably received in bearings therefor in a top plate that is adapted to be fastened to the ram of the machine. On said base plate is a die block with holes spaced therein, and on the underside of said top plate is a plate-like member referred to as a pad, and in this pad the punches are retained.

In the procedure of making ready a die of the above description, the operator, preliminarily to securing the said pad to the said top plate, must see to it that each of the punches (secured, as it is, in a socket therefor in the pad) is in precise axial alignment so as to coincide with the axial alignment of the hole therefor in the die block, when the die will have been finally installed and is in readiness for the machine to be operated.

And again, in case any one or more of the punches may, during the operating of the machine, yield its precisely true alignment even though extremely slightly, fouling results, and there is immediately the necessity of removing the said pad, and of correcting the alignment of such punch or punches as have become deflected.

The punch being fitted and made fast rigidly in the socket therefor in the metal which constitutes said pad, the job of restoring to precise alignment, the punch which has become deflected has long been a problem and I am not aware that there has heretofore been designed an implement by which said aligning of the punch can be practicably accomplished. Whereas a procedure of swaging, as by a cold chisel or by a center punch, of the metal of the pad adjacent to the shank of the punch has hitherto been resorted to, experience has taught that in such a procedure the contour of the socket usually is distorted to such extent that the grip of the shank of the punch is rendered insufficiently tenacious. As a result, the affected punch, after a relatively short period of machine operation, again yields its true position of alignment.

My invention is based upon the idea that if the metal which is displaced by manually applying an implement thereto, may be displaced in such manner that the planiform contour of the

2

mass immediately at the shank of the punch may be not impaired, the rigid and dependable retention of the punch in the precise position to which it is aligned is assured.

5 To provide an implement of formation and function so that in its use manually, the metal of the pad, in an arcuate area thereof closely adjacent to the shank of the punch may be displaced and at the same time compressed to metal to metal union with the wall of the punch shank, is the specific aim of my invention.

My invention is embodied in the newly devised implement described in the following specification, defined in the claims, and illustrated in the 15 accompanying drawings.

In the drawings—

Figure 1 is a side view of my improved aligning implement, a portion thereof being shown in cross section.

20 Figure 2 is a top plan view in the direction of arrow 2 in Figure 1.

Figure 3 is an enlarged bottom plan view in the direction of arrow 3 in Figure 1.

25 Figure 4 is an enlarged side view of the working end portion of the implement, in the direction of arrow 4 in Figure 1.

Figure 5 is a cross section plan view, on the broken line 5—5 in Figure 4.

30 Figure 6 is a vertical central sectional view taken on the broken line 6—6 in the direction of arrow 6 in Figure 5.

Figure 7 is a diagrammatic view indicating the appearance of a conventional die structure equipped with a pad carrying a plurality of 35 punches, for example, four, two of which are spaced closely adjacent to each other.

Figure 8 is a top plan view taken on the broken line 8—8 in Figure 7.

40 Figure 9 is a diagrammatic view indicative of the appearance of the punch pad after it will have been removed from the die structure and disposed in inverted position on the worker's bench.

Figure 10 is an enlarged cross section view of 45 a fragmentary portion of the pad, said view being illustrative of a punch of conventional form.

Figure 11 is a top plan view of Figure 10.

50 My new implement, as typically illustrated in the drawings, consists of a tubular bar 14 of tool steel, with bore 16 of diameter slightly larger than the diameter of the punch which is to be aligned. The head portion of the implement embodies a solid integral body structure. Its exterior surface 17 may be knurled, and its head end 18 is of convex formation.

A major segmental portion 21 of the open end of the bar is cut away, as at an angle of about fifteen degrees to the right angle transverse plane of the end of the bar. The lesser segmental portion 23 of said open end of the bar, I designate as the working end of the bar. (See Figure 3.) It is of rounded formation in cross section (see Figure 6). The working edge 25 thus provided is blunt in cross section, is of about ninety degrees extent in planiform curvature, and is concentric with the bore of the implement.

On the exterior surface of the wall of the implement, in the portion thereof opposite to the perpendicular of the working edge 25 of the implement, is a sight which consists of an indented line 27 which is coincident with the longitudinal central plane that bisects the said working edge 25.

Preliminarily to using the implement, for example, in an instance wherein the affected punch is a part of equipment such as is indicated in Figure 7, the operator disposes the pad P (which will have been removed from the die structure, as is the practice when a punch will have become tilted from true alignment) in inverted position on the bench, as indicated in Figure 9. He now places a chalk mark 32 at a location on the surface of the pad immediately near the affected punch 31, which has become obliquely inclined to the pad. That is to say: inclined slightly from the perpendicular (see broken line in Figure 10). The said mark 32 is to indicate to the operator, the direction toward which the punch is to be tilted in order to restore it to perpendicular alignment.

The operator now lowers the implement (the punch being received in the bore 16 of the implement) to position with its working edge 25 engaged with the surface of the pad, seeing to it that the sight line 27 of the implement is in line with the chalk mark 32. Then, by a hammer blow applied to the head of the implement while said implement is held in the position above described, the working edge 25 is caused to indent the metal of the pad at the area thereof diametrically opposite to said mark 32, and thereby to displace a portion of said metal in an arcuate area 34 (see Figure 11) that is immediately near to and is concentric with the socket 35 and is concentric with the shank of the punch that is secured in said socket. Said displacement being, as it is, in the direction of and concentric with the united surfaces of the said socket and shank, the uniformity of the metal-to-metal union of the said socket and shank is not disturbed. At the same time, the pressure of the metal so displaced and crowded by the implement against the punch shank is such as to tilt the punch from its deflected position, to aligned position, and to rigidly hold it in the aligned position.

It will be understood of course that the usual resurfacing of the obverse side of the pad P is had to remove protrusion of any portion of the surface of the foot end 37 of any punch which will have had to be aligned.

The effect of said working edge 25 of the implement when impinged as above described upon the metal of the pad, being certain, positive and dependable, and the punch being sensitively responsive to the displacement of the metal at the

socket 35, the artisan is enabled to readily measure the amount of force suitable to be applied to the head of the implement in repeated hammer blows, to cause the punch to be transposed from the inclined position, to the desired perpendicular position. The implement being concentric with the punch, it is capable of being used effectively in instances where the punches are closely spaced (for example as indicated by the closely spaced punches indicated in Figure 7) and where the distance between the punches may be as slight as little more than the width of the wall of the implement.

The punch, at which the implement is applied, serving, as it does, to sustain the implement in upright position, the operator, in poising the implement, is concerned solely with the technique of properly locating the working edge 25 with regard to the direction in which the punch is to be crowded.

It will be understood that in supplying implements according to my invention, the diameter of the bore of each implement is dictated by the diameter of the punch to which it is to be applied. Also it will be understood that modifications may be made within the scope of the invention as it is defined in the claims, without departing from the spirit or principle of the invention.

30 What I claim as my invention is:

1. An implement of the kind described, consisting of a bar of tool steel hardened and tempered, the working portion thereof being tubular and having inside diameter slightly larger than the 35 diameter of the punch to which the implement is to be applied, a greater segmental portion of the rim of the working end of said bar being cut away, and the remaining segmental portion of said rim being rounded in cross section, and constituting 40 an arcuate and blunt working edge that is concentric with the internal face of said bar.

2. Same as claim 1, plus—and there being a sight line on the exterior surface of said bar extending from the plane of the center of said working edge and in parallelism with the longitudinal axis of said bar.

3. A punch aligning implement consisting of a tubular metal bar, a greater segmental portion of the rim of the bottom of said bar being cut away to constitute the remaining segmental portion an arcuate working edge, the plane of said working edge being at a right angle to a plane that is parallel with the plane of the longitudinal axis of the bar, and said working edge being of rounded formation in cross section.
